UNITED STATES PATENT OFFICE

2,005,873

SMOKING PIPE

Stanley S. Schaffer, Chicago, Ill.

Application December 6, 1933, Serial No. 701,113

7 Claims. (Cl. 131—12)

This invention pertains to a smoking pipe and particularly to improvements therein intended to enhance the functioning of the pipe and increase the enjoyment which may be obtained therefrom.

Of the moisture that collects in the ordinary straight stem pipe there are two sources, namely, condensation of oily and aqueous vapors in the tobacco itself and a certain amount of saliva 10 which may enter the mouthpiece. If the saliva be permitted to reach the bottom of the pipe bowl it adversely affects the quality of the smoke. On the other hand, if the natural condensation from the tobacco itself progresses along the pipe stem to the mouth of the smoker it interferes seriously 15 with the enjoyment of the smoke.

This invention aims to prevent either kind of moisture from moving from its source to the opposite end of the pipe stem.

Another advantage arising out of this invention is that the smoke in its travel is caused to traverse a longer path than it does in the ordinary pipe stem and in this longer travel becomes more directly exposed to the cooling action of 20 the atmosphere so that the smoke is actually considerably cooler when received into the mouth of the user.

Other objects and advantages of the invention relating to its functions and maintenance will 25 be more fully set forth hereinafter.

In the drawing a preferred embodiment of the invention is shown, the single figure disclosing a pipe made in accordance with this invention and shown in central vertical section.

The illustrated pipe has a bowl 1, a stem 2 and a mouthpiece 3 which fits snugly into the end of the stem in the manner illustrated and in accordance with time honored practices in pipe construction. A passage 4 leading from the 30 mouthpiece through to the bottom of the bowl is also shown, being the usual passage commonly found in pipes of this general character. The stem 2 is provided with an aperture 5 and a second aperture 6, as shown, into which the opposite ends of a tube 7 are thrust, the fit being merely a snug fit which will amply secure the tube in position and yet permit its removal with reasonable convenience. The end 8 of the tube terminates in full communication with the passage 4, the boring of the hole 5 being continued until such full communication is attained. Yet 35 the end 8 of the tube does not obstruct the passage.

The other end 9 of the tube sets down into the 40 passage 6 and is notched out at 11 on that half

of the tube which faces toward the bowl so that smoke from the bowl may flow into and up through the tube. The extremity 12 of the tube extends into the recess 13 in the bottom of the bore 6 and blocks the passage 4 so that neither smoke nor moisture may flow straight through the passage 4 in the pipe stem. The smoke must detour through the tube 7 while the condensation coming from the bowl will be deposited in the recess 13 and in the pipe stem between that point and the bottom of the bowl. The vertical wall of the end 9 of the tube will act as a condensing surface, particularly by reason of the fact that any heat imparted thereto by the smoke will be dissipated by conduction rapidly up to 10 the top of the U-shaped tube, thence into the atmosphere.

Saliva entering the mouthpiece, of course, cannot flow through the tube, and will be stopped in the passage by the extremity 12 of 20 the tube. It may, of course, collect in the passage between the apertures 5 and 6, which space serves as a reservoir and saves the smoke from passing through such accumulated moisture.

The U-shaped tube may readily be removed 25 from the pipe stem and cleaned with an ordinary flexible pipe cleaner and at the same time the horizontal passage 4 may be cleaned in the usual manner with a pipe cleaner. The holes 5 and 6, which may be straight sided or tapered, 30 after removal of the U-shaped tube may be cleaned easily with wads of cotton or paper. There being no sharp bends in the tube it can be readily cleaned with the well known cotton covered flexible wire pipe cleaners. Thus no difficulty will be experienced in keeping the entire 35 pipe perfectly clean.

It will be apparent that the tube 7 may be used with curved stems as well as straight stems.

The tube 7, by reason of its position, shape 40 and size, makes it convenient for the user to slip a finger between the legs of the tube and thus readily hold the pipe on the one finger alone. He can then use the other four fingers on his hand for handling whatever tools, books 45 or papers may be engaging his attention at the time. Therefore, when this feature of the invention is desired to be used the shape of the space between the legs of the tube will be dimensioned so that the finger of the user may be 50 wedged snugly therein.

The material from which the tube is made may be steel, aluminum or other appropriate metal easily fabricated into the shape shown or it may be a hard rubber composition, "Bakelite" 55

or some other substance suitable for conducting the smoke and capable of being manufactured in the shape shown.

It should be understood that this invention is susceptible of embodiment in forms which differ from the illustrated embodiment, and that such variations are comprehended within the scope of the appended claims.

Having shown and described this invention, I claim:

1. A pipe having a stem and bowl and a passage therethrough connected with the bottom of the bowl, and a removable U-shaped tube having one open end communicating with said passage without blocking the same and the other end communicating with the passage by means of an opening facing toward the bowl, a part of the wall of said tube being positioned to seal said passage between said opening and the mouthpiece, said passage being wholly unobstructed between the bowl and its open end except by said wall.
2. A pipe including a bowl, stem and mouthpiece, a passage extending directly through the mouthpiece and stem into said bowl, and a removable U-shaped tube piercing the stem at the top side thereof communicating with said passage at two longitudinally separated points, the end of the tube nearest the mouthpiece opening into the passage without obstructing the same while the other end nearer the bowl communicates with the passage only toward the bowl and has a wall intersecting the passage to seal the same, said passage being wholly unobstructed between the bowl and its open end except by said wall.
3. A pipe including a bowl and stem, the latter being provided with a passage extending from the bowl to the free end of the stem, a removable U-shaped tube entering the stem from the top side thereof through two spaced apart apertures, said apertures being provided in the stem extending upwardly from said passage and sufficiently spaced apart that the legs of the tube connecting them affords a space for insertion of a finger, the end of the tube nearest the bowl having a wall portion intersecting and obstructing the passage on the side toward the free end of the stem, the same end of the tube being notched to afford communication with the passage in the direction toward the bowl, the other end of the tube freely communicating with the passage nearer the free end of the stem without obstructing the same, said passage being wholly unobstructed between the bowl and its open end except by said wall.

4. A pipe including a bowl and stem provided with a passage extending from the bowl longitudinally through said stem, and a removable U-shaped tube having one end entering the stem from the top side thereof and a wall of said end

intersecting and blocking said passage, the opposite wall of said tube end being recessed to establish communication from the interior of the tube into the portion of the passage extending therefrom only toward said bowl, the middle portion of the tube extending above the stem and the other end of the tube extending into the stem with its open end communicating directly with said passage at a point further removed from said bowl, without obstructing said passage, said passage through the stem being wholly unobstructed except by a wall portion of the tube end nearest the bowl.

5. A pipe including a bowl, stem and mouthpiece provided with a passage extending from the bowl longitudinally through said stem and mouthpiece, spaced apart apertures being provided in said stem leading from said passage upwardly through the top surface of the stem and in open communication with said passage, and a U-shaped tube with its ends snugly but removably fitted into said apertures, the tube end remote from the bowl communicating with the passage without obstructing it, the end nearest the bowl having a wall portion thereof traversing and sealing said passage between the two apertures and being notched to establish communication from the bowl through the passage thence through the tube to the mouthpiece, said passage through the stem being wholly unobstructed except by a wall portion of the tube end nearest the bowl.

6. A pipe including a bowl, stem and mouthpiece and having a passage extending from the bowl directly through said stem and mouthpiece, and a U-shaped tube piercing the stem from the top side thereof downwardly into said passage, the tube end nearest the mouthpiece communicating with the passage but not obstructing it while the end nearest the bowl has a depending wall sealing the passage, and is notched to establish communication from the bowl through the passage and tube to the mouthpiece.

7. A pipe including a bowl, stem and mouthpiece and having a passage extending from the bowl directly through said stem and mouthpiece, and a U-shaped tube having its ends piercing the stem from the top side thereof downwardly into said passage, the tube end nearest the mouthpiece communicating with the passage but not obstructing it, the tube end nearest the bowl being provided with means sealing the passage in a direction extending toward the mouthpiece while affording communication from the tube into the passage toward and into said bowl, the passage being unobstructed between the bowl and mouthpiece except by said means, the tube and said means thereon being bodily removable from the stem to completely open said passage for cleaning purposes.

STANLEY S. SCHAFER.
